UNITED STATES PATENT OFFICE.

JOSEPH H. HERBST, HYMAN FASS, AND MAURICE SHANK, OF NEW YORK, N. Y.

PASSENGER-CAR.

No. 887,804.

Specification of Letters Patent.

Patented May 19, 1908.

Application filed December 24, 1907. Serial No. 407,958.

To all whom it may concern:

Be it known that we, JOSEPH H. HERBST and HYMAN FASS, subjects of the Emperor of Austria-Hungary; and MAURICE SHANK, a citizen of the United States, all residing at New York, in the county and State of New York, have invented certain new and useful Improvements in Passenger-Cars, of which the following is a specification, reference being had to the accompanying drawings.

Our invention relates to improvements in passenger cars; and an object of our invention is to provide a passenger car having means for preventing the passengers who are entering the car from interfering with the movements of the passengers who are leaving it.

Another object of our invention is to provide a passenger car with means whereby the entrance of the passengers operates a register which is beyond the control of the conductor who is made responsible for all fares registered.

In the drawings illustrating the principle 25 of our invention and the best mode now known to us of applying that principle, Figure 1 is a rear end view partly in section; Fig. 2 is a section on the line A—A of Fig. 1; Fig. 3 is a side elevation of the rear end of 30 the car, the steps being broken away for the purpose of clearness; and Figs. 4 and 5 are details of the turnstile mechanism herein-after described.

The car body *a* is fitted with the seats *b* 35 and is supported upon the wheels *c* which travel on the rails *d*. The rear platform *e* is provided with a partition wall *f* which extends more than half-way across the platform and is formed at its inner edge with an 40 opening or slot *g* in which travels back and forth the slidable door *h*. Between the latter and the opposite wall *i* of the car is placed a turnstile the shaft *j* of which carries the arms *k* by which it is turned by the passengers as they enter and pass from the outer 45 compartment *s* to the inner compartment *t*. The object of the slidable door *h* is to permit of the use of shorter arms *k* than would otherwise be possible and thereby to economize 50 room for the installation of the turnstile. The shaft *j* of the latter carries at its lower end a gear *m* which drives a pinion *n* to which is pivotally secured one end of a connecting rod or pitman *o* the other end of 55 which is pivotally connected to a downwardly extending arm *p* which is fastened to

the slidable door *h* near the lower edge of the latter. To admit a passenger, the turnstile is adapted and designed to make a quarter-turn; and the ratio of the gear *m* to the pinion *n* is such that a quarter-turn of the gear drives the pinion around once, thereby moving the slidable door back and forth once. In the initial position of the turnstile, a narrow interval exists between the inner edge 60 of the door and the nearest arm *k* of the turnstile; but this interval is not sufficient to permit a person to pass between the end of the arm and the door. Upon pushing the arm *k* in the direction of the arrow in 70 Fig. 2, the door *h* is moved rapidly away from the turnstile and gives room for the passage of the person operating the turnstile, the arm *p* traveling in the slot *g* in the floor *r* of the platform; and after the passenger 75 has passed beyond the door, the further rotation of the turnstile moves the door rapidly in towards the turnstile to its initial position. The curved partition wall *u* serves to make the entering passenger operate the 80 turnstile until he has advanced it a complete quarter-turn; and it also serves to shield the turnstile from the view of the outgoing passenger, who is thereby saved the annoyance of starting in that direction to make his exit. 85 The wall *u* prevents the turnstile's being used by outgoing passengers, while the ratchet *v* (Figs. 4 and 5) in combination with the spring-controlled pawl *w* prevents the turning of the turnstile in more than one 90 direction. The upper end of the turnstile shaft *j* is connected through the bevel gears *x* and the shaft *y* with the register *z* (Fig. 3) so that a quarter-turn of the shaft *j* advances the register one unit. The register is suitably incased to prevent tampering with its parts by the conductor or other unauthorized person.

The inner compartment *t* is provided with an exit door 2 upon which is plainly marked 100 the word, "Exit", in order to warn the entering passenger not to attempt to gain admission to the car through that door. The latter opens only outwardly and closes automatically. The floor of the inner compartment *t* is formed with a curved slot 3 (Fig. 2) in which travels a rod 4 the upper end of which is fastened to the exit door 2 and the lower end of which is pivotally connected to one end of a locking lever 5 through the link 105 6 (see the dotted lines in Fig. 2). The free end of the locking lever 5 is formed with a

nose 7 which is adapted and designed to engage the teeth of the ratchet 8 mounted on the lower end of the turnstile shaft *j* (Figs. 1, 4 and 5). When the exit door 2 is swung outwardly by the outgoing passenger, the nose 7 engages the ratchet teeth (Fig. 4) and locks the turnstile, whereby the entrance of passengers is prevented during the time passengers in the car are leaving it. A spring 10 dog 9 mounted upon the wall *u'* engages the notched disk 10 on the turnstile shaft and arrests the rotation of the latter at the end of every quarter-turn.

From the foregoing description taken in connection with the drawings, it will be evident that the entering passengers are so separated from the outgoing passengers that the movements of neither class of passengers is interfered with by the other. Further, the conductor is left free to concentrate his attention upon the matter of the collection of fares from the incoming passengers and is made responsible for the collection of all fares by reason of the fact that he does not participate in the registering of the fares and must account for all fares registered by the operation of the turnstile.

We claim.

1. The combination with a partition, of a swinging arm the free end of which is separated from said partition by an interval; a door slidable across said interval into close proximity with the free end of said arm; and mechanism actuated by the rotation of said arm for moving said slidable door across said interval.

2. The combination with a swinging arm, of a slidable door the edge of which is separated from the free end of said arm by an interval; and mechanism actuated by the rotation of said arm for bringing the edge of said slidable door into close proximity with the free end of said arm.

3. The combination with a car platform, of a partition wall mounted thereon; a turnstile mounted on said platform and separated from said wall by an interval; and a slidable door which is moved back and forth across said interval between said partition wall and turnstile by the rotation of the latter.

4. The combination with an entrance door, of an exit door; and means actuated by said exit door for locking said entrance door.

5. The combination with a turnstile, of an

exit door; and means actuated by said exit door for locking said turnstile.

6. The combination with a car platform, of a partition which separates the inner part of the platform from the outer part thereof; a device which controls the passage from the outer to the inner part of said platform; an exit door for the inner part of the platform; and means actuated by said exit door for locking the said device against movement.

7. The combination with a car platform, of a partition which separates said platform into two parts; an entrance door which controls the passage from one of said parts to the other thereof; an exit door which controls the passage from one of said parts to the outside; and means actuated by said exit door for locking said entrance door.

8. The combination with a car provided with a platform, of registering mechanism mounted in said car; a gate the movement of which actuates said mechanism; and a partition which divides said platform into two parts, the passage from one of said parts to the other thereof being controlled by said gate.

9. The combination with a car platform, of a partition which divides said platform into two parts; a door which controls the passage from one of said parts to the other thereof; and a wall which shields from view said door.

10. The combination with a turnstile, of a door an edge of which is movable into close proximity with the free ends of the arms of said turnstile successively by the rotation of said turnstile.

11. The combination with a partition having an opening therethrough, of a turnstile mounted in said opening and separated from the edge of said partition by an interval; and a door movable across said interval by the rotation of said turnstile.

In testimony whereof we have hereunto set our hands at said New York city this twenty-first day of December A. D., 1907, in the presence of the two undersigned witnesses.

JOSEPH H. HERBST.
HYMAN FASS.
MAURICE SHANK.
